US00D916117S

(12) **United States Design Patent** (10) Patent No.: **US D916,117 S**
Downie et al. (45) Date of Patent: **** Apr. 13, 2021**

(54) **DISPLAY SCREEN WITH A GRAPHICAL USER INTERFACE FOR A COOLER PACK**

(71) Applicant: **MEDELA HOLDING AG**, Baar (CH)

(72) Inventors: **Kathy Downie**, McHenry, IL (US);
Carl Huval, McHenry, IL (US);
Claudia Kowanda, Oberägeri (CH)

(73) Assignee: **MEDELA HOLDING AG**, Baar (CH)

(***) Term: **15 Years**

(21) Appl. No.: **29/719,749**

(22) Filed: **Jan. 7, 2020**

(57) **CLAIM**

The ornamental design for a display screen with a graphical user interface for a cooler pack, as shown and described.

DESCRIPTION

The FIGURE is a front view of a display screen with a graphical user interface for a cooler pack. The broken lines in the drawings depict a display screen, or portions of the graphical user interface of the display screen with a graphical user interface for a cooler pack, and form no part of the claimed design.
